SCUFF

Silvia Dorée, New York, N. Y.

Application December 2, 1939, Serial No. 307,243

7 Claims.

(Cl. 36—9)

This invention relates to scuffs or slippers.

An object of this invention is to provide a scuff or slipper which will fit various sized feet and which is provided with means to retain the scuff on the foot.

Another object of this invention is to provide a scuff having water-proof sole and heel portions, and which is soft and foldable, so that the entire scuff may be rolled into compact shape.

Yet another object of this invention is to provide a scuff in which the front or vamp portion is connected to the rear or counter portion by a flexible, resilient shank portion, to permit extension of the length of the scuff, and also to permit the counter portion to be folded about said shank portion forwardly into the vamp portion, so that the scuff may be compactly packed.

Still another object of this invention is to provide a scuff having a counter portion with a strap at the front, and means at the instep portion of the vamp adapted to be engaged by the strap, to retain the scuff on the foot.

Still a further object of this invention is to provide a scuff which will accommodate feet of various widths.

A still further object of this invention is to provide a strong and durable scuff of the character described, which shall be relatively inexpensive to manufacture, comfortable to wear, attractive in appearance, easy to don and doff, and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown various possible illustrative embodiments of this invention,

Fig. 1 is a perspective view of a scuff, embodying the invention, on a foot;

Fig. 2 is a bottom plan view of the improved scuff;

Fig. 3 is an elevational, cross-sectional view taken on line 3—3 of Fig. 2;

Fig. 4 is a cross-sectional view taken on line 4—4 of Fig. 3;

Fig. 5 is a cross-sectional view taken on line 5—5 of Fig. 3;

Fig. 6 is a cross-sectional view taken on line 6—6 of Fig. 3;

Fig. 7 is a cross-sectional view taken on line 7—7 of Fig. 3;

Fig. 7a is a view similar to Fig. 7, but showing

the seam between the outer cover and lining at the vamp when the scuff is on a large foot;

Fig. 8 is a side elevational view of a scuff embodying the invention, and illustrating a modified construction, suitable particularly for a man's foot;

Fig. 9 is an elevational, cross-sectional view of the scuff shown in Fig. 8;

Fig. 10 is a cross-sectional view taken on line 10—10 of Fig. 8; and

Fig. 11 is a cross-sectional view taken on line 11—11 of Fig. 8.

Referring now in detail to the drawings, 10 designates a scuff or slipper embodying the invention. The same comprises generally of a front or vamp portion 11, and a rear or counter portion 12 interconnected by a shank portion 14.

The vamp portion 11 comprises an under-sole portion 15 and an inner-sole portion 16, stitched together all around by stitching 17. The sole portion 15 may be made of "Fabrikoid," or the like flexible, water-proof material.

The inner-sole portion 16 is preferably made of a soft woven plush, preferably having a high nap.

Stitched to the sole by the stitching 17, is an outer cover 18 and an inner lining 19 therefor. The outer cover may be made of knitted velvet, and the inner lining of any suitable cloth such as knitted fluff. The lining 19 is stitched to the outer cover 18 by a line of stitching 20, extending around the rear edges of said lining and cover, the thread used for the stitching preferably being elastic.

35 The outer cover 18 is Shirred or gathered by a line of elastic stitching 21 across the instep and below the upper edge 22 of the vamp. The outer ends of the line of stitching 21 meet the line of stitching 20 on opposite sides of the instep. Stitched to the portion 23 of the vamp, bounded by the lines of stitching 21 and 20, and disposed above the line of stitching 21, are a pair of pom-poms 24, or other decorative articles, located at the instep.

40 The counter portion 12 comprises a bottom or under-sole 30, likewise made of "Fabrikoid," or the like flexible, soft, water-proof material, and an inner sole 31 of woven plush having a high nap. The under-sole 30 is stitched to the inner-sole 31 by a line of stitching 32. Stitched to the under-sole and inner-sole, by said line of stitching 32, is an outer counter portion 33 and an inner lining 34 therefor. The lining 34 is stitched to the outer cover 33 by vertical lines of stitching 35 at the front of the counter, and a top line of stitching 36 extending all around the rear of the counter.

45 The outer cover 33 is likewise preferably made of knitted velvet or the like soft, flexible ma-

terial, and the inner lining 34 is also made of soft, flexible cloth, such as knitted fluff.

The shank 14 is preferably made of chenille elastic webbing, or the like elastic material, and is stitched at the ends thereof to the vamp and counter portions by lines of stitching 17 and 32.

Interconnecting the upper front edges 40 of the counter portion, is an elastic strap 41, likewise preferably made of chenille elastic webbing. When the scuff is worn on the foot, the strap 41 is pulled over and beneath the pom-poms 24, to keep the vamp from coming off the foot.

The outer cover 18 is preferably cut larger than the inner lining 19, to permit rolling of the seamed edge 20 which connects the lining to the outer cover, when a relatively large foot is put into the vamp. Since the outer cover and lining are both made of soft, flexible cloth, the seamed portion may roll, as illustrated in Fig. 7a of the drawings. Furthermore, both the lining and the outer cover being made of knitted fabric, have elasticity to permit stretching; and the elastic stitching 20, as well as the Shirred stitching 21, provides for expansion, so that the foot is snugly gripped around the arch and instep.

It will be obvious that the elastic vamp 14 may be stretched to permit the scuff to be worn by feet of various lengths.

In Figs. 8, 9, 10 and 11, there is illustrated a scuff 10a, embodying a modified form of the invention, and suited more particularly for men.

The scuff 10a comprises likewise a vamp portion 50 and a counter portion 51 interconnected by an elastic shank portion 52, preferably made of chenille elastic webbing. The vamp portion 50 comprises likewise an under-sole 54 of "Fabrikoid," or the like flexible, water-proof material, and an inner-sole 55 of woven plush having a high nap.

Stitched to the under-sole and inner-sole, is an outer cover 59 and lining 60 therefor, constructed substantially similarly to the outer cover 18 and inner lining 19, and they are stitched together by an elastic seam 60a. The outer cover is gathered at the instep, as at 60b, by elastic thread. In the scuff 10a, however, the pom-poms may be omitted and the shank 52 extends not only at the bottom, but around the arch of the foot. The shank portion 52 is thus of substantially semi-circular or curved cross-section. Furthermore, the outer cover 65 and the lining 66 of the counter portion are made of the same materials as the counter of scuff 10, and are stitched together by an elastic seam 67 at the upper edge of the counter.

The scuff 10a will remain on the foot because of the gathered portion 60b on the vamp, the elastic seam 60a at the rear edge of the vamp, and the elastic seam 67 at the upper edge of the counter.

It will be noted that the scuffs 10 and 10a are entirely soft and contain no stiff or rigid parts. The vamp may be rolled or folded about the elastic shank portion, so that the counter portion may be tucked into the vamp portion, for packing or for shipping purposes.

The scuffs are extremely comfortable to wear and fit sizes of various lengths and widths and will not come off the feet.

It will thus be seen that there is provided a device in which the several objects of this invention are achieved, and which is well adapted to meet the conditions of practical use.

As various possible embodiments might be made of the above invention, and as various

changes might be made in the embodiments above set forth, it is to be understood that all matter herein set forth or shown in the accompanying drawings is to be interpreted as illustrative and not in a limiting sense.

Having thus described my invention, I claim as new and desire to secure by Letters Patent:

1. A scuff comprising fore and rear foot engaging portions spaced from each other, and a stretchable section interconnecting said fore and rear portions, the fore portion including a vamp having its instep engaging portion gathered by an elastic thread.

15 2. A scuff comprising fore and rear foot engaging portions spaced from each other, and a stretchable section interconnecting said fore and rear portions, the fore portion including a vamp having its instep engaging portion gathered by an elastic thread, an elastic strap interconnecting the sides of the rear foot engaging portion, and means on the vamp to be engaged by the strap to keep the scuff on the foot.

25 3. A scuff comprising fore and rear foot engaging portions spaced from each other, and a stretchable section interconnecting said fore and rear portions, the fore portion including a vamp and the rear portion having sides interconnected by an elastic strap, and means on the vamp to be disengageably engaged by an intermediate portion of said strap to hold the strap in direct engagement with the vamp and to retain the scuff on the foot.

30 4. A scuff comprising fore and rear foot engaging portions spaced from each other, and a stretchable section interconnecting said fore and rear portions, the fore portion including a vamp comprising an inner lining and an outer cover, the rear edge of said inner lining being stitched to the rear edge of the outer cover, and said 40 vamp having its instep engaging portion gathered by an elastic thread forming a line of stitching disposed across the instep engaging portion.

45 5. A scuff comprising fore and rear foot engaging portions spaced from each other, and a stretchable section interconnecting said fore and rear portions, the fore portion including a vamp comprising an inner lining and an outer cover, the rear edges of said outer cover and inner lining being stitched together to form a seam, said outer cover and lining being made of soft flexible material, and said outer cover being cut larger than the lining.

55 6. A scuff comprising fore and rear foot engaging portions spaced from each other, and a stretchable section interconnecting said fore and rear portions, said fore portion including a vamp comprising an outer cover and inner lining therefor, the rear edges of said outer cover and inner lining being stitched together by an elastic 60 thread, said vamp having its instep engaging portion gathered by an elastic thread forming a line of stitching spaced from the seam which attaches the rear edge of the cover to the rear edge of the lining.

65 7. A scuff comprising fore and rear foot engaging portions spaced from each other, and a stretchable section interconnecting said fore and rear portions, the fore portion including a vamp having its instep engaging portion gathered by an elastic thread, said fore and rear foot engaging portions being made of soft flexible material.

SILVIA DORÉE.
